UNITED STATES PATENT OFFICE

163,641

APRON OR SIMILAR ARTICLE

Daniel B. Schwartzman, Englewood, N. J.

Application November 4, 1950, Serial No. 12,846

Term of patent 7 years

(Cl. D3—26)

To all whom it may concern:

Be it known that I, Daniel B. Schwartzman, a citizen of the United States, residing at Englewood, in the county of Bergen and State of New Jersey, have invented a new, original, and ornamental Design for an Apron or Similar Article, of which the following is a specification, reference being had to the accompanying drawing, forming part thereof.

In the drawing the figure is a front perspective view of an apron or similar article, showing my new design;

I claim:

The ornamental design for an apron or similar article, as shown.

DANIEL B. SCHWARTZMAN.
